BRAKE SHOE

Edward C. Folsom, Toledo, Ohio, assignor, by
mesne assignments, to The American Brake
Shoe and Foundry Company

Application March 17, 1934, Serial No. 716,086

7 Claims. (Cl. 188—258)

This invention relates to wrought metal reinforcement and assembly features.

This invention has utility when incorporated in metallic brake shoes, especially for wheels for rolling stock. As shown, there is key anchoring of the metal back as a reinforcement for the shoe.

Referring to the drawing:

Fig. 1 is a plan view of the sheet metal strap back reinforcement for a brake shoe;

Fig. 2 is a section on the line II—II, Fig. 1;

Fig. 3 is a section on the line III—III, Fig. 1;

Fig. 4 is a section on the line IV—IV, Fig. 1;

Fig. 5 is a side elevation of the back reinforcement of Fig. 1 showing the arch in section;

Fig. 6 is a medial longitudinal section through the shoe; and

Fig. 7 is a plan view of the back of the shoe.

A sheet metal back is provided having general arch form configuring to the radius of curvature for the shoe, say of the railway rolling stock. This reinforcement has flat termini

1 having therein an opening 2. These openings are centrally of the longitudinal axis of the reinforcement. Between these terminal openings 2 is an inward depression 3 as a groove or channel on the outer side providing rib 4 on the inward side. In this channel 3 are plurality of openings 5. These openings are located away from mid-position 6 of this arch reinforcement, and at this mid-position 6 drop side and depressed marginal portions 7 of the general extent of the depression 3 and in the same direction have medially reverse throw or raised portions 8. These upward throw re-

verse portions 8 provide re-entrant portions 9 forming a narrowed region in which hook-over termini 10 of the arch may assemble therewith.

These hook-over portions 10 have riser portions 11 abutting the narrowed portions 9 and have cross-over 12 therebetween. This reinforcement is thus of two portions. The sheet metal main back between the drop sides 7 and the central longitudinal depressions 3 has par-

45 parallel extending portions 13, 14. It is thus seen that there is in effect a longitudinally extending medial reinforcement rib of this depression 3, or marginally thereof there is a pair of longitudinally extending ribs 13, 14. It is noted

50 that there is continuity of the metal for full cross section past the narrowed portion 8. This is with absence of any cut out and involves additionally strengthening due to the reinforcing rib 3, which rib has continuity past the

55 arch 12 at the portion 6. This establishes a

rigidity for this construction, especially at the mounting lug provided at the arch 12.

With this as the skeleton of wrought metal, the cast of the brake shoe thereabout has general body 15 with back extension 16 at the termini with projection 17 to effect the keying through the openings 2. Additionally, through the openings 5 there is flow body portion to keying mass 18 in the depression 3. About the arch riser portion 12 there is enveloping cast 19 from the body mass of the shoe.

In this general structure there is provision for a shoe of simple form which may have chilled termini 20 in the body 15 and thus provide a structure of substantial form in maintaining 15 its mounting and general structure even as undergoing extremes of wear and the hazards of unusual traffic conditions. Side portions 7 have body portions 21 flowed thereover for marginal keying or anchoring of the back.

What is claimed and it is desired to secure by Letters Patent is:

1. A brake shoe comprising a body, a sheet metal back, and a mounting lug, said back having a longitudinally extending depression for the major extent thereof, said depression extending past said lug and away from said lug in opposite directions, said depression having anchor openings through which the body protrudes to overlap the edges of said opening. 30

2. A brake shoe comprising a body, a sheet metal back, and a mounting lug, there being a supplementary reinforcement for the back past the lug including a depression medially of the back, longitudinally past said lug, in opposite 35 directions, said back being raised on opposite sides adjacent the lug.

3. A brake shoe comprising a body, a sheet metal back, and a mounting lug, said back having termini and therebetween parallel depression portions longitudinally of the back, at least one of said depression portions being continuous past the lug, in opposite directions, and said back at the lug being imperforate in its transverse extent. 40

4. A brake shoe comprising a body, a mounting lug, and a sheet metal back having medially thereof terminal and intermediate openings in a longitudinal series, and a central depression continuous past the lug in opposite directions between the terminal openings in which the intermediate openings are located to serve as keying means for the body as protruding there-through to overlap the edges of said openings. 50

5. A brake shoe comprising a body, a sheet 55

metal back, said back having a central depression longitudinally of its extent and medially of its extent being marginally raised oppositely to the groove to provide a narrowed region, and 5 a hook member arch at said narrowed region.

6. A brake shoe comprising a body, a sheet metal back, and a mounting lug, said back having medially of its extent terminal and intermediate openings in a longitudinal series spaced 10 from the lug, and a depression between the terminal openings in which the intermediate openings are located, said body having key assembly with the back through said terminal openings in providing thickened termini for the shoe, 15 said body through said intermediate openings

overlapping the edges of said openings to provide a key along said groove, and said back adjacent said lug being raised to provide lug anchoring within the width of the body.

7. A brake shoe comprising a body, a sheet metal back, and a mounting lug, said back having, medially of its extent and longitudinally thereof, in opposite directions, a depression with keying opening means through the depression spaced away from the lug for the body portion to communicate with and lodge in the depression overlapping the edges of said opening means. 5 10
